UNITED STATES PATENT OFFICE.

WALTER E. HUENEFELD, OF CINCINNATI, OHIO, ASSIGNOR TO THE HUENEFELD COMPANY, OF CINCINNATI, OHIO.

HYDROCARBON-BURNER.

1,070,607.

Specification of Letters Patent. Patented Aug. 19, 1913.

Application filed October 10, 1912. Serial No. 724,972.

To all whom it may concern:

Be it known that I, WALTER E. HUENEFELD, a citizen of the United States, residing at Cincinnati, in the county of Hamilton 5 and State of Ohio, have invented certain new and useful Improvements in Hydrocarbon-Burners; and I do hereby declare the following to be a full, clear, and exact description of the invention, such as will 10 enable others skilled in the art to which it appertains to make and use the same.

This invention relates to improvements in hydrocarbon burners and particularly to such as are adapted for use with oil stoves,— 15 the object of my present invention being to so construct the device as to keep the inner wick tube cool and reduce to a minimum the undesirable effect of sudden drafts of air, upon the flame on the wick.

With this and other objects in view, the invention consists in certain novel features of construction and combinations of parts as hereinafter set forth and pointed out in the claims.

In the accompanying drawings, Figure 1 is a sectional view of the device with the parts in their normal operative positions. Fig. 2 is a view showing the parts forming the combustion chamber in elevated position, 30 and Figs. 3 and 4 are detail views.

1 represents the wick tube member and 2 the combustion chamber member of the burner. The wick tube member comprises concentric tubes 3—4 forming a wick chamber between them to receive a wick 5,—a perforated holder 6 being provided for the latter to coöperate with suitable raising and lowering means. The outer wick tube is provided at its upper end with an outwardly projecting depressed flange or seat 7, and the inner wick tube is provided at its upper end with an inwardly projecting flange 8, from the inner edge of which, a ring 9 projects upwardly. From the upper edge of said ring, 45 an annular flange or seat 10 projects inwardly and may be provided at its inner edge with a depending rib 11.

The combustion chamber member 2 comprises concentric foraminated shells 12—13 spaced from each other to form a combustion chamber 14 between them, which is in line with the wick. The shells are inclosed by a casing 15 which is spaced from the outer shell 13 and is open at its upper end, 55 the lower end of said casing being provided

with an inwardly projecting perforated flange 16. The shells 12—13 and casing 15 are secured together by means of cross rods 17.

The lower end of the shell 13 is seated 60 (when the parts are in their normal working positions) upon the outer depressed flange or seat 7 at the upper end of the wick tube 3. The inner foraminated shell 12 is provided at its upper end with a perforated 65 cap 18 and at its lower end (which terminates a short distance above the horizontal plane of the lower end of the shell 13) is provided with a perforated cap 19 which rests (near its peripheral portion) upon the 70 seat 10 at the upper end of the inner wick tube 4. Thus it will be seen that the foraminated shells of the combustion chamber member are supported respectively, upon the 75 seats 7 and 10 of the wick tube member, with the combustion chamber 14 immediately over and in direct alinement with the wick, and that the weight of the parts will insure the firm seating of said foraminated shells.

The lower cap 19 is constructed with an annular series of radial lugs or fingers 20 and the lower end of the shell 12 is notched to accommodate said lugs or fingers,—the lugs 21 formed by thus notching the lower 85 end of the shell being bent under the edge of the cap 19 and serving to retain the latter in place. The lugs or fingers 20 enter the combustion chamber 14 and project a sufficient distance across the lower portion of 90 the same to be in line with the wick and constitute limiting means for the latter. From this construction, it will be observed that the wick limiting lugs or fingers are made integral with the lower cap of the 95 inner shell 12 and that said lugs or fingers are therefore vertically movable with the combustion chamber member away from and toward the wick, but that when the burner is in operation, said limiting devices may be 100 in more or less proximity to the wick (according to the adjustment of the latter) without detracting from the efficiency of the flame on the wick.

A tube 22 is secured at its upper end to the lower cap 19 and, projecting downwardly through the opening formed by the annular flanges 10—11, enters the space within the wick tube member. The tube 22 is provided near its upper end with a plu- 105 110

rality of holes 22^a, and below said holes, a diaphragm 22^b is fixed within said tube. With such construction, drafts of air directly through the tube will be prevented by the 5 diaphragm 22^b, the air entering the lower end of the wick tube member being compelled to pass upwardly through the space between the inner wick tube 4 and the tube 22 and close to said inner wick tube; through 10 the holes 22^a and then upwardly through the perforated cap 19 into the inner shell of the combustion chamber member. With such construction, the inner wick tube will be kept cool and undesirable effects upon the 15 flame by sudden drafts of air will be reduced to a minimum, the passage of air through the burner being retarded and kept practically uniform.

The tube 22 constitutes a guide for the 20 vertical movements of the combustion chamber member, when the latter is raised or lowered by means of devices such as will now be described.

A ring 23 is located within the cylindrical 25 space formed by the inner wick tube and is provided with arms 24 rigidly secured in any suitable manner to the interior of the inner wick tube and with a plurality of upwardly projecting arms 25 corresponding in 30 number with a plurality of pins 26 which project inwardly from the wall of the tube 22 near the lower end of the latter. Each arm 25 is provided at one side with a diagonal edge 27 and at the upper end of each 35 diagonal edge, a horizontal seat 28 is formed and at one end of the latter, a lug 29 projects upwardly so as to form a stop shoulder 30. At the side of each arm 25 opposite the diagonal or inclined edge thereof, a horizontal 40 slot 31 is formed,—the lower wall of the horizontal slot in one arm forming, in effect, a continuation of the inclined or diagonal edge of the adjacent arm but at an angle to said edge.

45 When the combustion chamber member is in its normal operative position, the inwardly projecting pins 26 of the guide tube 22 will be disposed in the horizontal elongated slots 31 of the arms 24 and said combustion chamber member will be locked in its lower operative position. When it is desired to raise the combustion chamber member above the wick tube member, the operator will turn said combustion chamber member in one direction so as to cause the pins 26 to ride on the inclined edges 27 of the arms 25. When the pins 26 shall have reached the upper ends of said inclined edges, a further turning movement of the guide tube 60 will cause said pins to become disposed upon

the horizontal seats 28 at the upper ends of the arms 25 and thus the combustion chamber member will be sustained in its elevated position. Engagement of the pins 26 with the stop shoulders 30 will prevent the combustion chamber member and guide tube from being turned too far. It is apparent that by turning the combustion chamber member in the reverse direction, the pins 26 will be moved off of the horizontal seats 28, 70 and when said pins reach the inclined edges 27 of arms 25, the weight of the combustion chamber member will be sufficient to cause said pins to ride down the inclined edges and enter the elongated slots 31, thus causing the 75 combustion chamber member to become disengaged in operative position on the wick tube member and to be locked in such position.

While I have shown and described the manner of supporting the combustion chamber member on the wick tube member, and also wick limiting means, I do not herein claim these features specifically,—the same constituting the subject matter of my co-operating application Serial No. 724,971. 80

Having fully described my invention what I claim as new and desire to secure by Letters Patent, is:

1. In a hydrocarbon burner, the combination with a wick-tube member, and a combustion chamber member having a perforated bottom cap, of a tube secured to said bottom cap and movable in and guided by said wick tube member, said tube having holes below its upper end, and a diaphragm 90 within said tube below the plane of said holes, the wall of said tube below the plane of said diaphragm being imperforate. 95

2. In a hydrocarbon burner, the combination with a wick tube member, and a combustion chamber member provided with a perforated bottom cap, of a tube open at both ends and provided with holes near its upper end, said tube secured to said bottom cap and entering and guided by the wick tube member, a diaphragm within said tube below the plane of said holes, and raising and lowering devices secured within the wick tube member, said raising and lowering devices entering said tube and co-operating therewith to raise or lower the combustion chamber member when the latter is turned. 100

105 In testimony whereof, I have signed this specification in the presence of two subscribing witnesses.

WALTER E. HUENEFELD.
